UNITED STATES PATENT OFFICE

RUDOLPH BIRMAN, OF TRENTON, NEW JERSEY, ASSIGNOR TO DE LAVAL STEAM TURBINE COMPANY, OF TRENTON, NEW JERSEY, A CORPORATION OF NEW JERSEY

TURBINE CONSTRUCTION

Application filed January 24, 1930. Serial No. 423,001.

The present invention relates to elastic fluid turbines and particularly to marine turbines capable of operating in opposite directions to produce both ahead and astern movements of a ship.

Owing to the fact that a marine turbine must operate through all ranges of speed up to its maximum, it must be equipped with what is known as a stiff shaft of heavy, short construction the critical speed of which is sufficiently above the maximum running speed.

In view of the fact that the length of such shaft must be an absolute minimum, the usual form of such turbine includes ahead and astern wheels on the same shaft receiving steam at the respective ends of the shaft and discharging into a common exhaust casing on the central portion of the shaft, the wheel of the last ahead stage facing the wheel of the last astern stage. The space between these last stages must be as short as possible whereby the exhaust space is very limited.

However, if this space is quite short and of restricted size, the discharge from the ahead stages will flow into the last astern stage exerting a braking effect on the blades of the astern rotor and involving a disturbance of flow with consequent loss of power and efficiency. A similar braking action results from the action of the astern discharge on the blades of the last ahead stage.

To prevent such interference, partition walls have sometimes been introduced to separate the ahead and astern discharge passages at least in the vicinity of the blading where the harmful interference of the ahead flow with the idle astern blading or of the astern flow with the ahead blading can take place. Such partition walls if properly shaped and curved accomplish their purpose of guiding the flow of exhaust steam so as to prevent interference, but they use up more axial length than can be efficiently sacrificed in modern marine turbines.

It is the broad object of the present invention to provide a novel guide structure which leads the steam with practically no loss of energy from either the ahead or astern blading into the exhaust casing or volute from whence it may pass to the condenser in the usual way.

The improved guiding construction not only accomplishes this result effectively but also positively prevents the exhaust from the ahead stages from interfering with the idle rotation of the astern blades, and in a similar way makes it impossible for the astern exhaust to hit the ahead blades.

These and more detailed objects will be apparent from the following description read in conjunction with the accompanying drawings in which:

Fig. 1 is a sectional view showing a turbine in which the invention is incorporated;

Fig. 2 is a fragmentary elevation of the guiding unit; and

Fig. 3 is a plan view of the guiding unit.

The turbine casing is indicated by 2, there being mounted therein in suitable bearings the shaft 4 of the stiff type carrying the ahead wheels 6 and astern wheels 10 receiving, as usual, steam respectively from the steam chests 8 and 12 into which steam is selectively admitted depending upon the direction of rotation of the shaft, and therefore of movement of the ship, which is desired.

Between the last stages of the two sets of wheels is the exhaust receiving space taking the form of an annular chamber 14 communicating with the discharge 15 leading to a condenser.

If nothing were interposed between the last stages, it is obvious that the discharge from either would reach the blades of the other creating braking action. In the improved construction there is interposed guiding means for preventing such interference, said unit comprising a pair of outer annular rings 16 fitting into the casing and joined to an inner ring 18 by spaced webs 20 between which are carried annularly arranged guiding elements 22 of the general L-shape in cross section. In small units these various members may be comprised in a single casting; large units may consist of various sections suitably secured together.

In the preferred form as shown, the L-shaped guiding elements are arranged, as viewed in axial cross section, diagonally in a line extending approximately from the outer portions of the blades of the last ahead

stage to the inner portions of the blades of the last astern stage, the axially extending legs of the elements extending towards the last ahead stage. By suitably curving the guiding elements, the exhaust from the last ahead stage is turned from its approximately axial direction to an approximate radial direction, the latter direction being substantially assumed before the exhaust passes from the 10 guiding influence of the elements whereby there results no tendency for the exhaust to flow into the astern blading. The guiding elements have sharp inlet and discharge edges, and the steam passages between the adjacent elements may be of constant area throughout or of increasing area, if the space permits, to give a diffusing effect. By the provision of such guiding elements and an upturned shoulder 24 on ring 18, it will be seen that the discharge from the ahead stages 15 is smoothly guided to the discharge passage without substantial loss in a manner indicated by the full arrows.

As was just stated, the guiding elements 20 are of sufficient radial extent to turn the ahead exhaust to a substantially radial direction. They are, however, of as little radial extent as possible so as to offer a maximum passage for the exhaust from the astern 25 stages to the discharge, the flow taking place as indicated by the dotted arrows. By reason of the overlapping arrangement of the 30 guiding elements as viewed from the astern stages, the flow of astern exhaust to the ahead 35 blading is prevented.

By the above construction it will be seen 40 that the space between the ahead and astern wheels is so fitted out with guiding elements so that interference is prevented without any 45 increase in size, the exhaust from either of the stages having a full unrestricted space for its 50 passage. This feature is due to the fact that the same space, indicated by the zones where the two sets of arrows overlap, functions 55 as part of the discharge passage for each of the separate exhausts. Since the two exhausts do not take place simultaneously, this double function of the space is possible.

It will be understood that the above 60 description is purely illustrative of a preferred construction in connection with one form of turbine since the details of arrangement of the guiding elements, their number, etc. must necessarily depend upon the relationship of the 65 wheels of the two portions of the turbine.

What I claim and desire to protect by Letters Patent is:

1. A turbine including a casing, a shaft, 70 at least two spaced wheels mounted on the shaft and each including a set of buckets, means for guiding fluid to the first set of buckets for rotating the shaft in one direction, means for guiding fluid to the second set of buckets for rotating the shaft in the opposite direction, the exhaust from both sets 75

of buckets passing into the space between the wheels, a discharge passage located radially outwardly of said space, and means for guiding the exhaust from the respective sets of buckets to the discharge passage, said means including guide vanes arranged approximately between the outer ends of the buckets of the first set and the inner ends of the buckets of the second set, and forming passages the intake ends of which are aligned with the exhaust from the first set of buckets and the discharge ends of which are directed outwardly towards the discharge passage, the guide vanes overlapping as viewed from the second set of buckets so as to prevent direct passage of the exhaust from said second set to the first set, and terminating at their outermost portions to provide a passage of substantial free area from the second set of buckets to the discharge passage. 80

2. A turbine including a casing, a shaft, at least two spaced wheels mounted on the shaft and each including a set of buckets, means for guiding fluid to the first set of buckets for rotating the shaft in one direction, means for guiding fluid to the second set of buckets for rotating the shaft in the opposite direction, the exhaust from both sets of buckets passing into the space between the wheels, a discharge passage located radially outwardly of said space, and means for guiding the exhaust from the respective sets of buckets to the discharge passage, said means including annular guide vanes arranged approximately between the outer ends of the buckets of the first set and the inner ends of the buckets of the second set, and forming annular passages the intake ends of which are aligned with the exhaust from the first set of buckets and the discharge ends of which are directed outwardly towards the discharge passage, the guide vanes overlapping as viewed from the second set of buckets so as to prevent direct passage of the exhaust from said second set to the first set, and terminating at their outermost portions to provide a passage of substantial free area from the second set of buckets to the discharge passage. 90

3. A turbine including a casing, a shaft, at least two spaced wheels mounted on the shaft and each including a set of buckets, means for guiding fluid to the first set of buckets for rotating the shaft in one direction, means for guiding fluid to the second set of buckets for rotating the shaft in the opposite direction, the exhaust from both sets of buckets passing into the space between the wheels, a discharge passage located radially outwardly of said space, and means for guiding the exhaust from the respective sets of buckets to the discharge passage, said means including guide vanes of L-shape in axial cross section arranged approximately between the outer ends of the buckets of the first set and the 100

inner ends of the buckets of the second set, and forming passages the intake ends of which are aligned with the exhaust from the first set of buckets and the discharge ends of which are directed outwardly towards the discharge passage, the guide vanes overlapping as viewed from the second set of buckets so as to prevent direct passage of the exhaust from said second set to the first set, and terminating at their outermost portions to provide a passage of substantial free area from the second set of buckets to the discharge passage.

4. A turbine including a casing, a shaft, at least two spaced wheels mounted on the shaft and each including a set of buckets, means for guiding fluid to the first set of buckets for rotating the shaft in one direction, means for guiding fluid to the second set of buckets for rotating the shaft in the opposite direction, the exhaust from both sets of buckets passing into the space between the wheels, a discharge passage located radially outwardly of said space, and means for guiding the exhaust from the respective sets of buckets to the discharge passage, said means including annular guide vanes of L-shape in axial cross section arranged approximately between the outer ends of the buckets of the first set and the inner ends of the buckets of the second set, and forming annular passages the intake ends of which are aligned with the exhaust from the first set of buckets and the discharge ends of which are directed outwardly towards the discharge passage, the guide vanes overlapping as viewed from the second set of buckets so as to prevent direct passage of the exhaust from said second set to the first set, and terminating at their outermost portions to provide a passage of substantial free area from the second set of buckets to the discharge passage.

In testimony of which invention, I have hereunto set my hand, at Trenton, N. J., on this 20th day of January, 1930.

RUDOLPH BIRMANN.
